UNITED STATES PATENT OFFICE.

FRANK A. RYTHON, OF CHICAGO, ILLINOIS.

CORN-SHOCKER.

SPECIFICATION forming part of Letters Patent No. 764,381, dated July 5, 1904.

Application filed October 2, 1903. Serial No. 175,434. (No model.)

To all whom it may concern:

Be it known that I, FRANK A. RYTHON, a citizen of the United States, residing at Chicago, in the county of Cook and State of Illinois, have invented certain new and useful Improvements in Corn-Shockers, of which the following is a complete specification.

Heretofore in this class of machines a windlass operated by manual power has been used to raise the shock from the platform preparatory to swinging it from and depositing it at the side of the machine.

The object of this invention is to provide a device whereby the draft-animals of the machine may be employed to raise the shock from the platform. To accomplish this, I provide means as set forth in the accompanying drawings, in which—

Figure 1 is a rear view of a corn-shocking machine embodying my improvement. Fig. 2 is a plan view of the same with parts removed. Fig. 3 is a perspective of the draft-tongue and evener of a corn-shocker, showing the essential elements of my improvement in connection therewith. Fig. 4 is a side elevation of the tongue, showing the improvement mounted thereon and also a view of the crane and sheaves with a rope connection to the shock-forming standard of the machine.

This view is partly diagrammatic, as some of the elements are shown not in their true relative positions, but in positions to illustrate the principle of the operation of the mechanism. Fig. 5 is a perspective of the notched retention-bar. Fig. 6 is a detail perspective showing the construction of the foot-trip which actuates the pawl controlling the notched retention-bar, and Fig. 7 is an enlarged perspective of this pawl.

While this invention can be applied to any style of corn-shocking machine, it is particularly applicable to the type shown in Patents No. 724,515, of April 7, 1903, and No. 734,973, of July 28, 1903.

More specifically stated, the invention relates to connecting a notched bar to the evener of the machine, this bar being so constructed that it can be locked or detained in any desired position longitudinally relative to the tongue of the machine, the power for oper-

ating the machine being transmitted from the draft-animals therethrough. The rear end of this bar connects with what would otherwise be the fixed end of the windlass-rope, the arrangement being such that as the retention-bar is released and the draft-animals advance the machine will remain stationary and the effect of the pull will be applied to raise the shock through the said retention-bar and connecting-rope. As the other end of the rope connects with the windlass, the shock may be raised by manual effort, if desired.

Only those parts of the machine directly connected with and affected by this improvement will be described herein. For a detailed description of the general construction of this type of machine reference may be had to the patents cited.

Referring to the drawings, A represents the main frame of the corn-shocker; B and B', the supporting-wheels; C, the rotating shock-forming table; D, the gatherers, and E the draft-tongue.

F designates the shock-forming standard, detachably mounted upon and rotatable with the shock-forming table C, and is provided with the arms f.

G represents the main standard of the crane, rigidly secured to the frame of the machine, and G' is the boom mounted thereon.

The main standard G is supported by the braces g, and the juncture of these braces with the said standard is effected through the casting H. On this casting H is rotatably mounted the casting I, to which is pivotally secured the said boom G'. The boom G' overhangs the shock-forming table C, the free end thereof being substantially vertically coincident with the shock-forming standard F, mounted on said table.

J is a manually-operated windlass supported upon the standard G and the stubble-ward braces g and around which passes the rope J', the said rope extending upwardly over the sheave j, which is secured to the upper end of the standard G. The rope extends from this sheave to and passes over one of the double sheaves j', which is secured to the free end of the boom G'. Passing down from this sheave j' the rope engages a movable sheave 100

j^2 . As heretofore constructed the rope returned to the free end of the boom G' and was made fast thereto. Instead of this construction, however, the previously-fixed end of the 5 rope is returned over the double sheave j' , then through a second sheave j^3 , secured to the upper end of the standard G , and from there passing to a sheave j^4 , (see Figs. 3 and 10 4,) over which it passes and connects with the draft device in a manner hereinafter described.

As nothing more is claimed in the above-mentioned elements, a general description thereof will suffice, it being of importance to point them out only for the fact that they are 15 associated or operatively connected with my improvement.

Referring to Figs. 3 and 4, e and e' designate plates or flanges secured to and arranged longitudinally of the draft-tongue E . These 20 plates or flanges form a slot in which pivots a double bell-crank lever having the arms k , k' , and k^2 . L is a notched retention-bar adapted to be received by and moved longitudinally in the slot just mentioned. In a hook l , formed 25 on the rear end of this retention-bar, is secured the rope J' , while the front end of said bar connects with the evener M .

The position of the double bell-crank is controlled by the rod N , which engages the arm 30 k^2 of said bell-crank and extends rearwardly to and connects with the foot-lever O , as shown in plan view in Fig. 2 and in detail in Fig. 6. This foot-lever consists of a transversely-extending portion which serves as the 35 fulcrum for the lever and the cranked ends which form the arms o and o' . To the arm o is connected the operating-rod N , while the arm o' serves as a foot-trip and is within reach of the operator's seat. At the free end 40 of the arm o' is a downwardly-turned end o^3 , the foot-lever as a whole being so located that this downwardly-turned end o^3 will engage the main driving-chain b of the machine, as shown in Fig. 2, when the foot-trip is depressed, and when so engaged it operates to 45 lock the machine. A coil-spring o^2 on the foot-trip O operates to move the arm o rearwardly or in a direction as indicated by the arrow in Fig. 6. On the forward end of the 50 rod N is secured the coil-spring n , which affords a yielding connection between the said rod N and the arm k^2 of the double bell-crank.

Secured to the evener M and longitudinally movable therewith is the forwardly-extending 55 member E' , consisting, preferably, of a pipe secured loosely to the tongue E by means of the eyebolts e^2 e^3 . To the forward end of this pipe E' is secured the neck-yoke of the draft-team by means of the U-bolt e^4 , the same 60 bolt securing to said pipe a stop e^4 , which operates to limit the rearward movement of the evener M and the pipe E' .

The operation of the device is as follows: The normal relative positions of the parts constituting my improvement are shown in Fig. 65

3, where the parts are held in these positions by the coil-spring o^2 on the foot-lever O operating through the controlling-rod N to depress the rearward arm k' of the double bell-crank until it engages one of the notches l^2 on 70 the forward end of the retention-bar L . This effectually locks the evener M to the tongue. When a shock is formed on the revolving platform C and it is desired to remove it, the foot-engaging portion o' of the foot-trip O is 75 depressed, pushing the rod N forward and compressing the spring n until the arm k is disengaged from its notch in the said retention-bar. In depressing the foot-lever O the hook l will be caused to engage the main 80 driving-chain b and lock the machine against further advance until released. The draft-animals are started and their pull, instead of advancing the machine, operates through the bar L and the rope J to lift the shock from 85 the table. When the shock is lifted to a sufficient height, the operator depresses the foot-lever until the arm k' of the bell-crank engages one of the notches l^2 in the retention-bar, in this way locking the retention-bar in 90 its forward position, as shown in dotted lines in Fig. 3. The shock will thus be held suspended above the table, and the operator swings the crane and shock to a position to deposit the latter at the side of the machine. 95 After the shock has been deposited the crane is swung back and again connected with the platform, the draft-animals backing sufficiently to permit of the reengagement of the standard with the table, which movement will 100 also bring the retention-bar back to its normal position, and the operator on releasing the foot-trip will permit the bar to be again locked in its normal position.

It is understood, of course, that the function of the pipe E' is to accommodate the forward movement of the neck-yoke secured to the draft-animals, the stop e^4 limiting the rearward motion of the said pipe relative to the tongue E . The pin l^4 in the rear end of the retention-bar L contacting the plates or flanges e and e' limits the forward movement of both the retention-bar and the pipe relative to the tongue, while the pin l^4 in the forward end of said bar limits the rearward movement of same.

What I claim as my invention, and desire to secure by Letters Patent, is—

1. In a corn-shocking machine, in combination, a shock-lifting crane, a draft-tongue and 110 evener slidably mounted thereon, a notched retention-bar connecting said evener with the shock-lifting crane and means for locking at will the said retention-bar to the said draft-tongue thereby preventing relative longitudinal movement of same in one direction or the other, substantially as described.

2. In a corn-shocking machine, in combination, a shock-lifting crane, a draft-tongue, an evener slidably mounted thereon, a retention- 115 120 125 130

bar connecting said evener with the shock-lifting crane, said retention-bar being provided at either end with notches having oppositely-disposed engaging surfaces, a three-arm bell-crank mounted in supports rigidly connected to the said draft-tongue the rearward arm of said bell-crank adapted to engage the notches on the forward end of the said retention-bar and thus prevent forward movement thereof while the forward arm of said

bell-crank is adapted to engage the notches on the rearward end of said retention-bar and prevent rearward movement thereof, and means connecting with the third arm of said bell-crank for operating same, substantially 15 as described.

FRANK A. RYTHON.
